UNITED STATES PATENT OFFICE.

DERRICK S. WEST, OF BOSTON, MASSACHUSETTS, ASSIGNOR, BY DIRECT AND MESNE ASSIGNMENTS, OF THREE-FOURTHS TO JOHN W. DREW, OF SAME PLACE, AND CHARLES H. FISH, OF MANCHESTER, NEW HAMPSHIRE.

MAGAZINE BREECH-LOADING GUN.

SPECIFICATION forming part of Letters Patent No. 478,728, dated July 12, 1892.

Application filed September 11, 1891. Serial No. 405,425. (No model.)

To all whom it may concern:

Be it known that I, DERRICK S. WEST, a citizen of the United States of America, and a resident of the city of Boston, in the county 5 of Suffolk and State of Massachusetts, have invented certain new and useful Improvements in Breech-Loading Firearms, of which the following is a full, clear, and exact description.

10 This invention in breech-loading firearms consists of improvements, substantially as hereinafter described, and pointed out in the claims, on the contrivances embraced by my application, Serial No. 396,965, for Letters Patent of the United States; but, as will be hereinafter obvious, they are in some, if not in all, respects as well applicable to breech-loading firearms of other constructions and arrangements.

20 In the drawings forming part of this specification, Figure 1 is a central, longitudinal, and vertical section of the gun and magazine barrels at their breech ends and of the receiver and stock in part, and a side view of 25 the breech-block closed, of the hammer at rest on the rear end of said block, of the cartridge-carrier in its normal position, and of the several mechanisms for operating them in their respective corresponding positions. Fig. 2 is 30 a similar section and view to Fig. 1, but showing the breech-block withdrawn or opened, the cartridge-carrier in its position presenting a cartridge for entrance into the gun-barrel, the hammer at full-cock, and the several 35 mechanisms for operating them in their respective corresponding positions. Fig. 3 is a transverse vertical section, line 3 3, Fig. 1. Fig. 4 is a transverse vertical section, line 4 4, Fig. 2. Fig. 5 is a central longitudinal vertical section of the breech-block, the hammer, 40 the cartridge-carrier, and the several mechanisms for operating them in their respective corresponding positions, excepting, however, that in some few portions the parts are removed either in whole or part, all as will hereinafter appear. Fig. 6 is a plan view of the cartridge-carrier in its normal position and a transverse and horizontal section of the receiver at and along each side of the carrier. 45 Fig. 7 is an elevation of the rear end of the

breech-block and of the part of its operating mechanism directly connected with it, and a transverse and vertical section of the receiver at each side of the breech-block and said mechanism. Fig. 8 is a detail section, hereinafter referred to.

In the drawings, A is the gun-barrel. B is the magazine-barrel for cartridges, and lying under and lengthwise of the barrel A and C is the stock, attached to the chamber or receiver D D² in upper and lower communicating portions and held in both barrels A and C at their breech ends, all as well known, except as hereinafter explained, and forming no part of this invention.

55 The upper portion D of the receiver D D² extends directly rearward from the breech of the barrel A to and terminates at a fixed abutment or wall C³ of the receiver. This wall is directly opposite to and in line with the barrel A. The lower portion of the receiver is below and continues rearward of said upper portion and of its said wall C³. The receiver at its upper side is open and is closed by a cover C³, which is adapted to be moved rectilinearly 60 forward and backward on grooves or ways C⁴ at the inner face of the opposite side walls C⁵ of the receiver D D².

65 E E² is the breech-block, divided transversely into two sections or parts, joined together by a hinge joint or pivot E³, which is entered horizontally across the section E and through a forward projection E¹⁰ of the section E², having an arm E¹¹ extended upward and angularly from it, and it and said arm fitted 70 and swinging within a slot or way of the forward breech-block section E and all otherwise, so that the breech-block sections can be butted end to end, and thereby closed against and made continuous with each other and so 75 that they can be swung and placed at an angle to and thus opened from each other, and, furthermore, the angular projection E¹⁰ E¹¹ of the section E² moved, as the case may be, either forward or backward, in the slot of the 80 forward breech-block section E, as and for a purpose as will hereinafter appear.

85 The sectional breech-block, straightened, is practically of a length equal to the upper portion D of the receiver D D², and thus placed 85

it fills said portion D from end to end and its forward end is in position, closing upon the breech of the barrel, and its other or farther end at rest against and in close contact with 5 the wall or abutment C² of the receiver.

The sectional breech-block, placed with its sections at an angle to each other, as stated, is then practically of less length than the upper portion D of the receiver, and this length 10 is such and the block lies in such manner relative to said portion D of the receiver that a sufficient part of the upper portion D of the receiver directly from the breech of the barrel is open to receive and enable a cartridge 15 to be inserted in and its shell afterward to be withdrawn from the barrel.

The section E of the breech-block E E² when the block is in the upper portion of the receiver is forward of its section E², and preferably it is the shorter in length. The forward breech-section E on its opposite sides and the opposite inner faces of the opposite side walls C⁵ of the receiver have longitudinal and engaging ribs E⁴ and grooves E⁵ severally extending lengthwise of said breech-block section and said side walls and all, so that the section being moved rectilinearly forward to and backward from the breech of the barrel will be positively guided, and in this connection it is to be understood that for each of 30 said movements of said forward section the rear section of the block is required to be suitably situated, all substantially as hereinafter explained.

35 The rear section E² of the breech-block E E² at its farther end portion and on its opposite side has similar projected lugs E⁶, and the opposite inner faces of the side walls C⁵ of the stock C have similar two-part grooves 40 E⁷ E⁸ to receive the lugs. The part E⁷ of each groove E⁷ E⁸ leads downward and at right angles and directly off from the rear end of a side groove E⁵ of the receiver, and the part E⁸ leads directly from the lower end of 45 the part E⁷ on a downward rearward incline and into the lower and rearward extended portion D² of the receiver D D², all so that the rear section E² of the breech-block can be moved downward from and out of the upper 50 portion D and into and along the lower portion D² of the receiver, drawing the forward section E of the breech-block with it and along the upper portion of the receiver and back from the breech of the barrel and placing 55 the breech-block at an angle, as stated, and so that it can be moved upward from the lower portion D² and into the upper portion D of the receiver, straightening the breech-block, as stated, and placing it lengthwise along said upper portion D of the receiver and end to end between the breech of the barrel and the abutment-wall C² of the receiver. By the first movement of the breech-block the upper portion D of the receiver D 60 D² is open for a cartridge to be inserted into and after its discharge for the shell to be removed from the barrel, and by the second

movement said portion D of the receiver D D² is filled with the breech-block and thereby the cartridge in the barrel and when fired is 70 confined by said block against backward movement because of the then resistance thereto of the rearward abutment-wall C² of the receiver, against which rests the rear end of the breech-block, and all otherwise, substantially as described in the application aforesaid and forming no part of this invention. 75

F F are links, one each side of the rear section E² of the breech-block. Each link at one end is jointed, as particularly shown, to said block by the studs or lugs E⁶ of said section, and at its opposite end each is jointed by a common cross-pin E¹⁷, held on both to the forward end of a rod or link F⁸, that at its rear 85 end is jointed to the forward end of a plate or block G, held on and at the under and outer side of the receiver, and thereon adapted to be moved lengthwise forward and backward and for a distance limited and determined by the length of a slot G⁶ in the under wall D³ of the receiver. The slide block or plate G in both its forward or normal position, Fig. 1, and its rearward position, Fig. 2, is back of the breech-block. 90

G² is an elongated or looped-shaped handle held on and projected from the under side of the slide-block G. This handle or slide is in forward and rearward sections, and each section contains and has respectively a trigger 100 H H² and a lever-catch S S², respectively fulcrumed on the slide and otherwise, as will hereinafter appear. 95

The trigger H H² is for action on the sear K, fulcrumed at K² on the receiver. The 105 catch S S² is for holding and fastening the slide G against accidental rearward movement from its forward position, Fig. 1, and to that end its arm S² has opposite side lugs S³ in position for engagement with lateral 110 notches G⁷, one at each side, and of a depth less than that of the guiding groove or way G⁶ for the movement of said slide. This engagement of catch S S² with the side notches G⁷ of the slideway G⁶, as above stated, is automatically made by means of a flat bent spring 115 S⁴, which is secured to the arm S² of said catch S S², and has a rest on the upper wall D⁴ of a chamber D⁵ of the receiver and above the groove G⁶. Said spring S⁴ crosses said 120 chamber D⁵ from side to side and from its under to its upper wall, and is so fitted to them as to shut off said chamber against the admission to it of extraneous matters as to the rearward end portion of the slideway G⁶, 125 traversed by said catch S S² in the forward and backward movement of the slide G. In both of said movements of the catch S S² its side lugs S³ rest and slide upon the under wall D³ of said chamber D⁵. 130

G⁸ are grooves, one at each side and running lengthwise of the slide G, and within and outside of the receiver the slide by its grooved portions laps beyond the opposite

parallel edges of its said guide-groove G^6 , and thus with the slide in its normal position, Fig. 1, said groove G^6 of the under wall D^3 of the receiver is shut off from the entrance of 5 extraneous matters therethrough to the receiver as to the forward end portion of said groove traversed by the slide in its forward and backward movements, as have been described.

- 10 L is the hammer, in the form of a bolt and, as shown in cross-section, cylindrical. This hammer is arranged in a correspondingly-shaped guideway L^6 at the upper side of the receiver and extending lengthwise in a direction more or less downwardly and rearwardly inclined to the longitudinal axis of the breech-block when the breech-block is closed or is within the upper portion D of the receiver D D^2 , and all otherwise for the hammer L at its forward end portion to pass through the fixed wall C^2 of said portion D of the receiver and into contact therewith at the end of the breech-block.

- 50
- 55
- 60

L^7 is a spiral spring lying lengthwise within the guideway L^6 for and confined end to end between the rearward end faces, respectively, of the hammer-bolt and said guideway. The backward or cocking movement of the hammer is against and its forward and firing movement is by the reaction of said spring. For convenience in cocking the hammer by the hand the hammer has a finger-piece or handle L^5 , engaging by its shank L^8 and adapted to move lengthwise a slot L^9 , which is at and along the upper wall of the guideway L^6 for the hammer, and is of suitable length, and also is covered or shielded against the passage therethrough of extraneous matters by an extension L^{10} , both forward and rearward of said handle. This slot L^9 and the shank connection of hammer L and its handle L^5 severally act as guides to the forward and backward movement of the hammer, and if said bolt is cylindrical, as shown, also to hold it against turning in its said guideway L^6 , and so insure the always proper presentation of the half and full cocking notches $L^2 L^3$ at the under side of the hammer for the sear K at its forward end K^4 to engage either of them as the hammer is moved backward to either half or fully cock it. The half-cocking notch L^2 of the hammer is undercut and the engaging end K^4 of the sear is of corresponding hook shape, all so that with the sear engaged with said notch the sear cannot be released from the hammer by the trigger H H^2 . The full-cocking notch L^3 of the hammer is not undercut, thus allowing the sear in engagement with it to be released by the trigger H H^2 when desired to throw the hammer. The sear K lies lengthwise in a slot L^{11} , and its fulcrum K^2 is under the guideway L^6 for the hammer.

K^3 is a flat spring, at one end rigidly held 65 on the receiver and at the other end at rest on and engaged with a shoulder K^5 at the upper side of the sear, and all so that the sear

will, as stated, automatically engage the hammer as the hammer is drawn or forced back and can be disengaged, as stated, from the 70 hammer by means of the arm H^2 of the trigger H H^2 acting on the downward and rearward extension K^6 of the sear K, provided, of course, the trigger is in the position shown in Fig. 1, and it is then pressed or pulled backward, as well known. 75

E^{13} is a recess or depression at the rearward end of the breech-block and of suitable shape to receive the forward end portion of the hammer, and all so that with the hammer engaged with said recess E^{13} of the breech-block the breech-block, as the gun is fired, is made fast against accidental movement from its closed or firing position within the upper portion D of the receiver. 85

The hammer at its forward end portion and below the engagement, as stated, of said portion with the breech-block, has an end face L^{12} , which is below said engaging end of the hammer and is opposite a cross-pin F^2 of the 90 link F of the double-link connection, before explained, of breech and sliding blocks E, E^2 , and G, that, at the beginning and for the first part of the opening or withdrawing movement of the breech-block caused by the rearward slide of the slide-block G, works on the hammer at its said face L^{12} , and thereby forces it backward for a portion of the length of its backward movement, preferably sufficient to half-cock it, on which by continuing said movement of the breech-block the rear end of the rearward section of the breech-block comes to a bearing on said end face L^{12} of the hammer, thereby further forcing the hammer backward and to full-cock, 95 whereupon said rear end of the breech-block escapes from said face L^{12} of the hammer, and the breech-block continues and completes its withdrawing movement, as before explained, and said end face L^{12} of the hammer 100 then enters to a groove E^{14} , Fig. 5, at and along the upper side of the rear section of the breech-block. Said face L^{12} of hammer L, against which the cross-pin F^2 of link F and rear end of breech-block works to cock the 105 hammer, all as explained, is particularly shown as at the forward end of a dog L^{13} , that at its rear end is entered into a recess L^{14} at the under side and is hung on a pivot L^{15} of the hammer, all so that the dog can have a 110 limited swing vertically to enable it to make better contact in the working thereon of said cross-pin F^4 of the link F, and the rear end of the breech-block, as has been described. 115

M M^2 is the firing-pin. This pin is in two 120 sections, one for each section of and together they extend for the full length of the breech-block, and the rear end of the section M^2 is in position to be struck by the hammer L, and the forward end of the section M is in position to strike and thereby to discharge the cartridge with which the gun-barrel is charged. The forward end of the rear section M^2 of firing-pin has a shoulder M^5 , and the 125

bore of said section has a similar shoulder, all so as to allow said section of the firing-pin to move sufficiently along its section of the breech-block to fire the cartridge, as explained, 5 and yet hold it against accidental escape from said section. The forward section M of the firing-pin has a slot M⁶ for a portion of its length, and this slot receives the angular portion E¹¹ of the arm extension at the forward 10 end of the rear section of the breech-block, all so that the forward section of the firing-pin is free for lengthwise movement to strike and thereby to discharge, as described, a cartridge in the gun-barrel, and is secure against 15 accidental escape, and, further, on the backward and withdrawing movement of the breech-block to open the breech of the gun-barrel said section M of the firing-pin is positively drawn backward and placed to the rear 20 of the front end of the forward section of the breech-block.

N is a spring-finger lying along and held on the upper side of and projecting by its downward hook end N² forward of the front 25 face of the forward section E of the breech-block. This spring-finger is the cartridge-extractor, and for that purpose it engages by its hook end the rim of the cartridge-shell, so that as the breech-block is drawn back from 30 the breech of the barrel the shell is withdrawn from the barrel for being afterward ejected or removed through the then open top of the upper portion D of the receiver, because of the simultaneous backward movement 35 of the cover C³, attached to the forward section of the breech-block.

O is an ear-piece or lug rigidly held on and projecting downward from the forward section of the breech-block and when the breech-block is filling the upper portion D of the receiver D D² standing centrally across the breech of the magazine-barrel. This lug O at the breech of the magazine-barrel, as stated, holds the cartridge or cartridge-follower, as 40 the case may be, which is presented toward it in and from leaving said barrel, it being of course understood that the magazine-barrel is adapted to force a cartridge or said follower out at the breech of said barrel, all as well 45 known. The lug O as the forward section of the breech-block moves from the breech of the gun-barrel A opens the magazine-barrel for the delivery of a cartridge then presented at its breech, and this cartridge as it is delivered 50 enters and is finally placed lengthwise upon the upper side of a block or cartridge-carrier P. This cartridge-carrier lies lengthwise between the side walls C⁵ of the receiver, and its forward end is free and its rear end 55 is hung on a center or fulcrum pin P² of the receiver. The cartridge-carrier in its normal position—that is, when the breech-block is closed on the breech of the gun-barrel and its lug O is across the breech of the magazine-barrel B—rests by its front and rear legs P⁴ on the floor of the receiver and is wholly 60 below the breech of the magazine-barrel, but

with its upper and transversely concave and cartridge-receiving surface in line with the lower side of the magazine-barrel to receive a 70 cartridge from said barrel. From this position of rest of the cartridge-carrier the carrier, swinging on its center pin P², can be placed in a position inclining downward and rearward from the breech of the gun-barrel, 75 or, in other words, in a position presenting the cartridge placed and lying upon it substantially in line with and its ball end at the breech of the gun-barrel. In this upward swing of the cartridge-carrier the next following cartridge of the magazine-barrel is held therein in the first instance by the bearing against it of the ball end of the cartridge on the carrier, and which at its opposite end is held against lengthwise movement on the carrier by its rest against the front edge of the lug O of the breech-block, and in the latter instance, and while the cartridge-carrier remains in its said upper portion and until its return to its normal position, by its forward 80 end P⁵.

P⁶ is a vertical and longitudinal slot of the cartridge-carrier, and it has at its opposite ends rearward and downward reclining and cam-acting walls P⁷ P⁸, respectively, the one 85 P⁷ at the rear end for the abutment of the cross-pin O² at the lower end portion of the lug O of the breech-block as said block moves backward, and the other P⁸ at the front end for the abutment of said cross-pin as the 90 breech-block moves forward, and all so that in the first instance to tilt or swing the cartridge-carrier upward and into the position stated relative to the gun-barrel and in the second instance to tilt or swing the cartridge-carrier downward and into the position as 95 relative to the magazine-barrel.

R R are vertical arms, one at each side of and each intermediately fulcrumed on and extended above the upper side of the cartridge-carrier, where each vertically is of bow shape and transversely and horizontally convex at its edge toward the side of the carrier. These arms are for holding the cartridge which is on the cartridge-carrier from being thrown 100 upward and off of the carrier as the carrier is being swung upward. To this end said arms R are closed over the top of the cartridge by the action of the upper and cam-shaped end R³ of each vertical curving groove R² at the inner face of each side wall C⁵ of the receiver, (see Fig. 3,) and from these said cams the upper ends of said arms on the downward movement of the carrier withdraw and enter into the deeper portion of the grooves in time for 105 them to be pressed apart by and thus to allow the rim of the cartridge to pass between them as the cartridge is forced forward by the breech-block in its forward movement into 110 the gun-barrel.

Q is the cartridge-ejector. This ejector consists of a plate, which is located in a vertical slit and has its lower end portion fulcrumed by the cross-pin O² on said lug O of the breech-

block and at its upper end portion a circular running slot Q^2 and pin Q^3 connection with said lug to allow the swing to a limited distance of the ejector on said lug O .

- 5 Q^4 is an angular notch at the corner of the front and upper edges of the ejector. The ejector in its normal position projects at its rear edge beyond the rear edge of the lug O , and there it has a bearing against the free 10 end of a bent spring Q^5 , which is held on the under side of the rear section of the breech-block, and also that as the breech-block is moving backward, extracting by the extractor N the cartridge-shell from the gun-barrel, the 15 rim of the cartridge at its lower side will be seated in the angular notch Q^4 of the ejector, then suitably pressed forward therefor by the spring Q^5 , and finally when the cartridge is wholly out of the gun-barrel it will be thrown 20 or jumped out of the receiver at its open upper side by a further and quick-acting pressure of said spring on the ejector, and which takes place before the lug O of the breech-block has reached and begun to act on the 25 rear incline or cam P^7 of the cartridge-carrier to tilt the carrier upward, as has been explained.

As is obvious, the foregoing description substantially embraces, but separately stated, 30 the operations of the several mechanisms making up the gun of this invention, and therefore it is now deemed necessary only to observe that said several operations are of course properly timed relatively to each other, 35 and all to the end of opening the breech of and extracting and ejecting the waste cartridge shell from the gun-barrel, and delivering and inserting a cartridge in and closing the breech of the gun-barrel, together with 40 cocking the hammer and placing the operating-trigger in position, when pulled, to free the hammer, and therewith and thereby fire the cartridge in the gun-barrel.

The upper portion D of the receiver $D D^2$ 45 for the forward section of the breech-block is cut away at E^{15} for a sufficient depth and length to allow said section and also the rear section of the breech-block and the connecting-links $F F^3$ to be all drawn therethrough 50 out of the receiver, first, however, having removed a cross-pin E^{16} of the receiver, provided as a guard against the forward section of the breech-block accidentally rising when moving through the rear end portion of its 55 guiding-groove of the receiver, and also having disconnected the link F^3 from the slide-block G , and which for this purpose only is connected to said slide just outside of the receiver.

60 Having thus described my invention, what I claim, and desire to secure by Letters Patent, is—

1. In a breech-loading firearm, in combination, a receiver having a guideway G^6 along 65 its under side and said way having a side notch or notches $G^7 G^7$, a slide G , held on and adapted to move lengthwise of said way and

suitably connected to the breech-block to move said block to open and close the breech of the gun, a chamber D^5 of and within the receiver 70 and lengthwise of the rearward part of said guideway G^6 , and a trigger $H H^2$ and a lever-catch $S S^2$, both independently fulcrumed on the slide, the trigger in advance of the catch and with the slide closed, so as to have the 75 trigger in position to release the hammer and the arm S^2 of said catch by side projections S^3 , adapted to engage with and disengage from said notches and to lap over and travel on the receiver at the sides of said way, 80 and also adapted to close said chamber D^5 and said way as the slide is moved forward and backward along said way, substantially as described, for the purposes specified.

2. In a breech-loading firearm, in combination, a breech-block in sections transversely of its length and said sections hinged and butted end to end and adapted placed end to end to close and placed at an angle with each other to open the breech of the gun, a link 90 F , pivoted to the rear section of the breech-block and having an abutment F^2 and otherwise suitably connected to move said breech-block to place its sections as aforesaid, a hammer L , held on and adapted to slide in a suitable guideway to be cocked and to discharge the gun, and an abutment L^{12} , held on and moving with said link and the rear section of said breech-block relatively adapted to contact in the movement of said breech-block to 100 open the breech of the gun, substantially as described, for the purposes specified.

3. In a breech-loading firearm, in combination, a breech-block in sections transversely of its length and said sections hinged and 105 abutted end to end and adapted placed end to end to close and placed at an angle with each other to open the breech of the gun, means adapted to move said breech-block to place its sections as stated, and a hammer, 110 having its striking end and the rear end of the breech-block struck by it in the discharge of the arm relatively adapted to interlock or engage with each other, substantially as described, for the purpose specified.

4. In a breech-loading firearm, in combination, a breech-block in sections transversely of its length and said sections hinged and butted end to end and adapted placed end to end to close and placed at an angle with each 120 other to open the breech of the gun, means adapted to move said breech-block to place its sections as stated, a firing-pin in sections, one to each section of and with the breech-block butted end to end in line with each 125 other and the forward section having a length-wiseslot M^6 , and an angular arm extension E^{11} , held on the section of the breech-block next to and pivoted on the forward breech-block section and entered into said slot of said section of the firing-pin, substantially as described, for the purpose specified.

5. In a breech-loading firearm, in combination, a breech-block in sections transversely

of its length and said sections hinged and butted end to end and adapted placed end to end to close and placed at an angle with each other to open the breech of the gun, means 5 adapted to move said breech-block to place its sections as stated, a cartridge-extractor and a cartridge-ejector both held on and moving with the forward section of said breech-block and the latter consisting, essentially, 10 of a vertical plate at its lower end fulcrumed and at its upper end having a notch to contact with the cartridge-rim, and a spring held on the section next to the forward section of the breech-block and adapted to bear on the 15 rear edge of said plate, substantially as described, for the purpose specified.

6. In a magazine breech-loading firearm having a magazine-barrel below the gun-barrel and open at its breech end, in combination, 20 a breech-block adapted to open and close the breech of the gun-barrel, a dependent lug O, held on and moving with said breech-block and at its lower end portion having a side projecting pin or pins O², and a cartridge-carrier P, located below and in line with the 25 breech-block and at its rear end fulcrumed to swing vertically and having a longitudinal slot P⁶, with downward and rearwardly-inclined and cam edges P⁷P⁸ for the travel of said 30 lug O and its abutment on said cams, substantially as described, for the purposes specified.

7. In a breech-loading firearm, a barrel, a stock, and a receiver, an abutment in the receiver to the rear of and in line with the barrel, 35 a breech-block resting when in closed position with one end against the abutment in the receiver and the other closing the breech of the barrel, said breech-block being divided transversely into front and rear sections 40 hinged to each other, an undercut recess in the rear end of the rear section of the breech-block, and a spring - actuated bolt passing through the abutment in the receiver and entering 45 said undercut recess, whereby the breech-block is locked in firing position, all substantially as described.

8. In a breech-loading gun, a barrel, a stock, and a receiver, an abutment in the receiver to the rear of and in line with the barrel, a 50 breech-block resting when in closed position with one end against the abutment in the receiver and the other closing the breech of the barrel, said breech-block being divided transversely into front and rear sections hinged to 55 each other, an undercut recess in the rear end of the rear section of the breech-block, a sectional firing-pin passing through the sec-

tions of said bolt and terminating in said recess, and a spring-actuated firing-bolt passing through the abutment in the receiver and entering 60 said undercut recess, whereby the breech-block is locked in firing position, all substantially as described.

9. In a breech-loading firearm, a breech-block moving horizontally rearward to open 65 the breech, a lug depending from the front end of the breech-block across the mouth of the magazine, a cartridge-carrier hinged at its rear end in the receiver beneath the breech-block, a slot in said carrier, through which 70 said depending lug passes on the opening of the breech-block, grooves in the side walls of said slot, terminating in a downwardly and rearwardly inclined cam-surface, and laterally-projecting pins on said lug traveling in 75 said grooves and engaging said cam-surface, all substantially as described.

10. In a breech-loading firearm, a transversely-divided breech-block having its sections hinged together, the front section moving in guideways horizontally rearward and the rear section obliquely downward and rearward to open the breech, an ejector-lever pivoted in a slot in a lower depending portion of the front section of the breech-block, a spring 80 attached to the rear section thereof and bearing against the rear face of the ejector, and an abutment in the receiver near the limit of the rearward throw of the breech-block and in the path of said ejector-lever, all substantially as described. 90

11. In a breech-loading firearm, a magazine, a barrel, a stock, and a receiver, a cartridge-carrier located in the receiver, means for moving it up and down in a vertical plane, curved 95 levers pivoted to and projecting from the opposite sides of said carrier, the pivots being intermediate the ends of said levers, and grooves in the opposite sides of the receiver, within which said levers travel on the upward and downward movement of the carrier, said grooves terminating both at the top and bottom in inwardly-inclined cam-surfaces, whereby the levers are opened by the lowering of the carrier and closed by the elevation 100 thereof, all substantially as described. 105

In testimony whereof I have hereunto set my hand in the presence of two subscribing witnesses.

DERRICK S. WEST.
